CLAIM

The ornamental design for a rear assembly for a motor home, as shown and described.

DESCRIPTION

FIG. 1 is a front side perspective view of the rear assembly for a motor home showing the new design;

FIG. 2 is a top plan view thereof;

FIG. 3 is a front elevational view thereof;

FIG. 4 is a left side elevational view thereof; and,

FIG. 5 is a right side elevational view thereof.

The broken line showing of a motor home in FIG. 1 is for illustrative purposes only and forms no part of the claimed design.
